UNITED STATES PATENT OFFICE.

JOHN L. COOPER, OF OAKDALE, TENNESSEE.

RAIL-JOINT.

1,128,107.

Specification of Letters Patent.

Patented Feb. 9, 1915.

Application filed June 23, 1914. Serial No. 846,881.

To all whom it may concern:

Be it known that I, JOHN L. COOPER, a citizen of the United States, residing at Oakdale, in the county of Morgan and State 5 of Tennessee, have invented new and useful Improvements in Rail-Joints, of which the following is a specification.

The present invention relates to means for bracing and connecting rails, and the 10 primary object of the invention is to construct a device of this character which shall be simple, comparatively cheap to manufacture and which will effectively brace and join rails to prevent the lateral movement 15 or the creeping of the rails.

With the above and other objects in view, the improvement resides in the construction, combination and arrangement of parts set forth in the following specification and falling 20 within the scope of the appended claim.

In the drawings: Figure 1 is a top plan view illustrating two rails connected in accordance with the present invention, Fig. 2 is a side elevation of the same, Fig. 3 is a 25 sectional view approximately on the line 3—3 of Fig. 2, Fig. 4 is a detail perspective view of the detachable side or wedge member, Fig. 5 is a plan view illustrating the device employed as a rail brace, Fig. 6 is a 30 side elevation of the same, Fig. 7 is a transverse sectional view approximately on the line 7—7 of Fig. 6, and Fig. 8 is a detail perspective view of the removable wedge member.

35 Referring now to the drawings and to Figs. 1 to 4 in particular, R—R designate two alining rails having abutting ends. The rails rest upon the base 1 of a chair 2, and the said chair has one of its edges 40 formed with an inturned flange 2 which overlies the base flanges of the rails at one side of the rails, while integrally formed with the flange 2 is a vertically projecting longitudinally extending plate 3 which enga- 45 gages in the fishing spaces of the rails and which is of a materially greater thickness than the flange 2. The base 1 is also of a greater thickness than the flange 2, so that the said flange provides what may be termed 50 a spring connection between the base 1 and the vertical plate 3. The opposite longitudinal edge of the base 1 is provided with an inwardly curved lip 4 which is of a length corresponding with the length of the chair 55 and which has its upper face 5 parallel with the straight longitudinally extending plate

3, but which has its inner and rounded face 6 beveled or inclined from one end of the chair to the opposite end thereof, so as to provide a wedge-shaped groove. 60

The numeral 7 designates the removable side for the chair. This side comprises an angle member, the vertical portion of which being shaped to be snugly received within the fishing spaces of the rails, and the horizontal portion 8 thereof having its under- 65 side extending downward and resting upon the horizontally straight upper face of the base 1, while the outer lower corner 10 of the member 7 is rounded, and inclined from 70 one end of the said member 7 to the opposite end thereof, thus providing the base of the member 7 with a wedge-shaped formation so that the same will be received by the lip and the rounded portion thereof engage 75 with the inclined rounded inner face or channel 6 provided by the lip 4. The vertical member of the side or fish plate 7 is provided with bolt openings which register with openings in the plate 3 of the chair 80 proper, securing elements in the nature of bolts 10 passing through the alining openings and said bolts being secured by nuts 11. The openings in the fish plate 7 are elongated, so that when the nuts 11 are 85 loosened the wedge-shaped side or fish plate 7 may be adjusted longitudinally of the chair and of the rails and when properly engaging with the chair and with the rails the nuts 11 will be screwed tight upon the 90 bolts 10. It is to be understood that the heads of the bolts 10 are of a sufficient size to contact with the outer face of the vertical portion of the fish plate 7, permitting the shanks to be snugly received within the 95 elongated openings in the said member 7. The chair, adjacent its opposite ends, is provided upon its longitudinal sides with flat lateral extensions 12, which are arranged in opposite pairs and spaced a suitable dis- 100 tance from each other so that each of the pairs will be received upon a tie 13. Centrally formed with the flat extensions 12 are ribs 14 and 15 respectively, the ribs 14 being also integrally formed with the flange 105 2 and the plate 3, and the ribs 15 being integrally formed with and bracing the lip 4.

Formed with the base 1 of the chair be- 110 tween and adjacent to the ledges 12 and de- pending from the said base are laterally ex- tending plates 16 which are adapted to abut

with the inner or adjacent faces of the ties 13, while connecting the said plates 16 is a centrally formed web 17 which is also integrally formed with the base 1. The plates 5 16 contacting with the ties 13 provide means for effectively preventing the creeping or longitudinal movement of the joint, while the bolts connecting the rails effectively prevent the creeping of the rails upon 10 the chair. The extensions 12 are formed with suitable spaced openings 18 receiving spikes 19 which enter the ties 13 and effectively hold the chair upon the tie.

In the remaining figures of the drawings 15 I have illustrated my device as in the nature of a rail brace, and in these figures the numeral 20 designates the base of the chair member, the said chair being provided adjacent one of its longitudinal edges with an 20 overlying flange 21 which terminates in a vertical plate 22, the flange 21 contacting with the base flange of the rail 23, while the plate 22 is received within the fishing space of the rail. The portion of the base projecting outwardly from the flange 21 has 25 centrally formed thereon adjacent its edges angular ribs 24 which are integrally formed with the flange 21 and with the plate 22, while the said extending portion opposite 30 the rib is provided with spike openings which receive the spikes 25 that secure the base of the chair to the tie 25'. The base 20 adjacent its opposite end is provided with an upturned inwardly extending hook 35 26 which has its inner and rounded wall 27 inclined from one of its ends to its opposite end to receive the wedge-shaped rounded edge 28 provided upon the base 29 of an angular side member or fish plate 30. The 40 plate 30 has its vertical member provided with an elongated opening 31 which is engaged by the head of a bolt 32 which passes through registering openings in the web of the rail and in the vertical plate 22 of the 45 chair, a nut 33 securing the bolt to the device, and the nut 33 is arranged between the reinforcing ribs 24. The hook 26 is centrally reinforced by a rib 34 which is arranged angularly from the portion of the 50 base 20 which extends outwardly of the hook and the said extending portion is pro-

vided with openings for the reception of spikes 35 which also enter the tie 25. The elongated opening in the fish plate permits of the proper adjustment of the fish plate upon 55 the chair proper and against the rail, while the bolt 32 passing through the opening in the web of the rail 23 and the round openings in the plate 22 serves as a means for preventing the creeping of the rail upon the 60 chair.

From the above description, taken in connection with the accompanying drawings, the simplicity of the device, as well as the advantages thereof will, it is thought, be 65 perfectly apparent to those skilled in the art to which such invention appertains without further detailed description.

Having thus described the invention, what I claim is:

In combination with railway rails, of a chair upon which the rails rest, said chair including a side which engages with one side of the rails, the said chair opposite the side being formed with an inwardly extending hook, the inner rounded wall of which being inclined from one end of the chair to the opposite end thereof, an angle plate having a rounded inclined corner which is engaged by the hook, the said angle plate 80 having its vertical member provided with longitudinal elongated openings, headed bolts passing through the openings and through round openings in the webs of the rail and the vertical member of the side of 85 the chair, and nuts for the bolts, the said chair having its base extended beyond its side and hook and provided with openings, ties upon which the chair rests disposed below the openings, spikes entering the openings and into the ties, transverse plates upon the base of the chair and contacting with the opposite inner faces of the ties, and a web formed with the base and centrally connecting the plates.

In testimony whereof I affix my signature in presence of two witnesses.

DR. JOHN L. COOPER.
